PICKER'S SACK CARRIER

Earl Lee Fugatt, Flintville, Tenn.

Application July 15, 1935, Serial No. 31,533

1 Claim. (Cl. 280—8)

This invention relates to a carrier for sacks of cotton or the like, the general object of the invention being to provide a wheel carrier of light weight for transporting the sack of cotton from one place to the other so as to eliminate dragging of the sack by the picker along the ground and to enable the picker to transport the sack from one place to another with but little effort.

This invention also consists in certain other features of construction and in the combination and arrangement of several parts to be herein-after fully described, illustrated in the accompanying drawing and specifically pointed out in the appended claim.

In describing the invention in detail, reference will be had to the accompanying drawing wherein like characters denote like or corresponding parts throughout the several views, and in which—

Figure 1 is an elevation of the device, and Figure 2 is a top plan view thereof.

Figure 3 is a section on the line 3—3 of Figure 1.

In the drawing, the numeral 1 designates an elongated substantially rectangular frame preferably formed of one piece of metal of rectangular cross-sectional shape, with its ends riveted together as shown at 2. A pair of side members 3 also formed of strap metal has one end fastened to the front end part of the under side of each side portion of the frame, with the member sloping downwardly and rearwardly as shown at 4 and then having a substantially straight part 5 from which the rest of the member slopes upwardly and rearwardly to a vertical part 6 which has its extremities bent and fastened to the under face of the side portion of the frame adjacent the rear end thereof. An axle-forming bar 7 extends across the frame slightly in front of the transverse center thereof and is connected to the upper part of the frame by rivets 8 or the like, and the ends of said bars extend vertically downwardly as shown at 9 with their extremities turned inwardly and pass into holes in the members 3, the said ends forming spindles for the wheels 10. A brace member 11 of substantially inverted U-shape has its bight portion connected with the frame and the bight part of the axle bar with its limbs extending downwardly and having holes therein for receiving the inner ends of the spindle forming parts of the axle, nuts 12 being threaded to the inner ends of the spindle parts. A platform 12

preferably of thin metal is fastened to the upper face of the frame 1. Loops 13 are connected to the front corner of the frame for receiving snap fasteners so that a sack with snap fasteners can be placed on the platform 12 with the snap fasteners engaging the loops for detachably holding the sack on the platform. I prefer to bend over the ends of the platform 12 for engagement with the ends of the frame 1 as shown at 14.

Light metal is used throughout the construction of the device so that the device will have but little weight and yet will be strong enough to support a filled cotton sack.

The device will enable a picker to transport a filled sack from one place to another with but little effort so as to eliminate the dragging of the sack along the ground which soon wears out the sack.

It is thought from the foregoing description that the advantages and novel features of the invention will be readily apparent.

It is to be understood that changes may be made in the construction and in the combination and arrangement of the several parts, provided that such changes fall within the scope of the appended claim.

Having thus described the invention what is claimed as new is:

A cotton sack carrier comprising a rectangular frame, an axle member extending transversely across the same in front of the transverse center of the frame, and having its ends extending downwardly and then bent inwardly to form spindles, a side bar on each side of the frame and having its ends connected with the under face of the side portions of the frame and provided with an intermediate substantially horizontal part having a hole therein for receiving the outer end of the spindle forming part, portions of the side bar sloping upwardly from said horizontal portion to the ends of the bar, an inverted U-shaped brace member connected with the under face of the central portion of the axle member and having holes in the ends of its limbs for receiving the ends of the spindle forming parts, means for holding the said spindle forming parts in said holes, and a wheel on each spindle forming part located between a limb of the inverted U-shape member and a side bar, a platform covering the frame.

EARL LEE FUGATT.
